GARMENT HANGER

Robert L. Hart, Manhasset Hills, N.Y., assignor to
W. R. Grace & Co., Duncan, S.C.

Filed Mar. 4, 1971, Ser. No. 121,223

Term of patent 14 years

Int. Cl. D6—08

U.S. Cl. D80—8

FIG. 2

FIG. 4

FIG. 3

FIG. 1 is a front elevational view of a garment hanger showing my new design;

FIG. 2 is a rear elevational view thereof;

FIG. 3 is an elevational view taken from one side thereof;

FIG. 4 is an elevational view taken from the side opposite that shown in FIG. 3; and

FIG. 5 is a bottom plan view thereof.

I claim:

The ornamental design for a garment hanger, as shown.
